US00D897367S

(12) **United States Design Patent** (10) Patent No.: **US D897,367 S**
(45) Date of Patent: **** Sep. 29, 2020**

(54) **DISPLAY SCREEN WITH GRAPHICAL USER INTERFACE**

(71) Applicant: **Jack Sargeant**, Delray Beach, FL (US)

(72) Inventor: **Jack Sargeant**, Delray Beach, FL (US)

(**) Term: **15 Years**

(21) Appl. No.: **29/717,552**

(22) Filed: **Dec. 18, 2019**

(51) LOC (12) Cl. **14-04**

(52) U.S. Cl.

USPC **D14/486**

(58) **Field of Classification Search**

USPC **D14/485-495**

CPC **G06Q 30/0281; G06F 3/04817; G06F**

3/0481; H04L 41/145; H04M 1/274558;

H04N 1/00424

(57) **CLAIM**

The ornamental design for a display screen with graphical user interface, as shown and described.

DESCRIPTION

The sole FIGURE is a front elevation view of a display screen with graphical user interface showing my new design.

The broken lines in the drawing showing a display screen form no part of the claimed design.

1 Claim, 1 Drawing Sheet
